UNITED STATES PATENT OFFICE

2,393,301

CONTROL SYSTEM FOR FURNACES

Carl H. Dicke, Dayton, Ohio, assignor to The Master Electric Company, a corporation of Ohio

Original application January 21, 1941, Serial No. 375,143. Divided and this application December 23, 1942, Serial No. 469,970

8 Claims. (Cl. 236—1)

This invention relates to improvements in control system for furnaces, and more particularly for furnaces adapted to alternatively burn two types of fuel. The instant application is a division of my co-pending application Serial Number 375,143, filed January 21, 1941 (Patent 2,335,263, November 30, 1943).

An object of this invention is to provide an arrangement for improving the year-round operation of furnaces.

Another object of this invention is to provide an improved controlling system for furnaces adapted to burn two types of fuel, such as coal and gas.

Still another object of this invention is to provide an economical, efficient, automatic and reliable control system for furnaces adapted to burn solid and gaseous fuel.

A further object of this invention is to control a furnace burning both solid or gaseous fuel in accordance with the will of the operator, by a single automatic temperature-responsive unit.

A still further object of this invention is the provision of an arrangement whereby a furnace may be changed over from solid to gaseous fuel operation, and vice versa, in the simplest possible manner.

A more specific object of this invention is to provide a correlated solid and gaseous fuel burning control system for furnaces, wherein the change-over from solid to gaseous fuel and vice versa is accomplished in the simplest possible manner from a single temperature-responsive unit, and the optimum conditions for either fuel burning operation are automatically assured.

These and other features, capabilities and advantages of the invention will appear from the subjoined detailed description of a preferred embodiment thereof, illustrated in the accompanying drawing, in which the single figure is a circuit diagram of a control system in accordance with the present invention, wherein the furnace damper and a gas valve are controlled by a single room thermostat.

The form of invention illustrated in the figure, illustrates a control system for a furnace generally indicated at 2, adapted to be supplied with both solid and fluid fuel. The furnace 2 will have suitable fire-controlling dampers for use in connection with the solid fuel, such as the draft damper 4, as well as means such as the pipe 6 for the entrance of the fluid fuel, which may be, for example, gas. The furnace is primarily under the control of a suitable temperature-responsive device such as the usual room thermostat 8, which

may be of the two-way or three-wire type. The latter is adapted to control the opening and closing of the dampers by suitable means such as the damper motor generally indicated at 10, and the magnetically operated, normally closed gas valve 12, depending upon the position of the season switch 14, in a manner to be described in more detail hereinafter. The system may also include a suitable basement switch 16 for use in connection with the firing of the solid fuel.

As shown in the figure, the room thermostat 8 is in its "off" position, the season switch 14 is in the position for solid fuel control, the basement switch 16 is in its normal position, the gas valve 12 is in its closed position, while draft damper 4 of furnace 2 is closed. If, now, the temperature of the space to be heated lowers sufficiently to move the room thermostat 8 to the "on" position, a circuit will be established beginning with one end of the transformer secondary winding 22, conductor 200, damper motor 78, conductors 106, 202, and 203, contact arm 36 and contact 38 of basement switch 16, conductor 204, arm 206, and closed contact 208, 210, of thermostat 8, conductor 212, contact arm 58, and contact 60 of season switch 14, conductor 214, brush 92, commutator segment 94, brush 96, and conductor 218, to the other side of winding 22. The damper motor 78 is accordingly energized to raise the damper 4 from the closed to the open position, the circuit for the damper motor being transferred from brush 92 to brush 102 by the commutator 94. This results from the fact that as the damper motor 78 is rotated, it also rotates the commutator 94 to such an extent that the brush 92 will meet the cut-out section 100, thus breaking the motor circuit through that brush; however, before the commutator has moved this far, the brush 102 will leave the cut-out section 104 and engage the commutator 94, thus maintaining the motor circuit through conductor 106, brush 102, commutator 94, to brush 96, independently of the brush 92. The motor will continue to rotate until the commutator has moved approximately 180°, or until the brush 102 is in the cut-out section 108, at which time the energizing circuit for the motor 78 will be entirely interrupted. However, at this point, a suitable crank 110 driven by the motor 78 and interconnected with the draft damper 4 by suitable means such as chain 112 will have moved the damper to the open position, to increase the combustion in the furnace in accordance with the call of the room thermostat.

If, now, the room thermostat 8 is satisfied and

returns to its "off" position, a circuit will be established for the damper motor 78 to return the damper 4 to its closed position. This circuit may be traced from one end of the transformer secondary winding 22, conductor 200, motor 78, conductors 106, 202, and 203, contact arm 36 and contact 38 of basement switch 16, conductor 204, arm 206, and closed contacts 208 and 220 of thermostat 8, conductor 222, brush 122, commutator 94, brush 96, and conductor 218 to the other side of winding 22. After the damper motor has started to rotate its control circuit will again be transferred to brush 102, and the damper 4 will be moved to its closed position. It will be seen that after the damper motor and commutators have moved slightly in a direction to close the damper, the brush 122 will fall within the cut-out section of the commutator, but again just before this happens, the brush 102 will have contacted the commutator 94, maintaining the energizing circuit for the motor 78 as previously traced when the motor was raising the draft damper. Also, similarly, when the motor has rotated approximately 180° and the draft damper is now closed, the brush 102 will fall within the cut-out portion 104 so that the motor will stop and the damper remain closed.

If, at any time, as during the spring and early fall, it is desired to operate the furnace on gas, the season switch 14, as seen in the drawing, is thrown to the left. If the room thermostat 8 is now moved to the "on" position, a closed circuit entirely independent of the source of power 18 will be established, while the circuits to the damper motor are interrupted. This closed circuit may be traced, for example, from arm 206 of room thermostat 8, conductor 204, contact 38 and contact arm 36 of basement switch 16, conductors 203 and 232, thermo-couple 224, conductor 228 energizing winding 140 for gas valve 12, conductor 230, contact 132, and contact arm 58 of season switch 14, conductor 212, and closed contacts 210 and 208 to the arm 206 of the thermostat. Power for energizing the coil 140 to raise the valve 12 is, in this case, derived from the thermo-couple 224 heated by the pilot 137. When the room thermostat is satisfied and its contacts are moved to "off" position, the closed circuit energizing the valve winding 140 will be opened, and the valve will accordingly close.

The system illustrated in the drawing is, as will have been noted, also provided with a suitable basement switch which may shunt the "on" contact of the room thermostat 8 to open the draft damper 4 for firing when the furnace is being run on solid fuel. If the basement switch 16 is moved to its "open" position, a damper-raising circuit for the damper motor will be established from one end of the transformer secondary winding 22, conductor 200, damper motor 78, conductors 106, 202, and 203, contact arm 36 and contact 144 of basement switch 16, conductor 234, contact arm 28 and contact 30 of the switch 14, conductors 236 and 214, brush 92, commutator 94, brush 96, and conductor 218 to the other end of winding 22. Again, after the motor has rotated a certain amount, control of its circuit will be transferred from brush 92 to brush 102 to complete the raising operation. If the season switch is in position for gas firing, movement of the basement switch to "open" position will be ineffectual to open the draft damper. This follows from the fact that when the basement switch is in its "open" position, the circuit for the damper motor must be traced through contact 30 of

the season switch 14, but this contact is engaged only when the season switch is in the solid fuel firing position.

Various changes in the above-described system will occur to those skilled in this art and are contemplated as forming part of the present invention. For example, additional safety limit switches may be added to the system where deemed desirable. While the system has been illustrated as operated upon low voltage, by a proper choice of equivalent parts the system may be used on any ordinary voltage. Additionally, various units forming the system have been diagrammatically indicated by way of illustration, and it will be obvious that well-known equivalent parts can be used in place of those shown. While no signal lamp has been illustrated as associated with the room thermostat, due to the fact that the ordinary thermo-metal will not provide enough power to both energize the valve controlling solenoid and a signal lamp, it is to be understood that another source of power other than the thermal couple might be used in this system, in which case the addition of a signal light might readily be included.

While, for the sake of simplicity, the damper motor has been illustrated as operating only a draft damper, it is to be understood that in accordance with usual practices, the damper motor may also operate a correlated check damper.

It has been found that the system illustrated and forming part of the present invention is unusually well adapted to control furnaces burning solid and gaseous fuels, since, in the fall and spring months a desirable level of heat is difficult to obtain with solid fuel alone, whereas gas is ideally suitable for heating at this time. Accordingly, it is contemplated that during the cold winter months the furnace will run on solid fuel, while during the fall and spring months the season switch will be thrown so that the furnace will run upon gas. However, it is clear that the invention in its broader aspects is not limited to such operation, but is generally adaptable for the control of the furnace burning solid and fluid fuel at any time. The control thermostat need not necessarily be a room thermostat and the fuel, so far as the control system is concerned, could be, for example, oil as well as gas.

Accordingly, while I have herein shown and described only certain embodiments of certain features of my invention, it is to be understood that they are to be regarded merely as illustrative, and that I do not intend to limit myself thereto except as may be required by the following claims.

I claim:

1. Controlling system for a furnace adapted to burn both solid and gaseous fuel, said furnace having at least one controlling damper movable between fire-retarding and fire-accelerating positions, and a gas supply, the combination of a main source of power, a damper motor for moving said damper from one of said positions to the other, a normally closed gas valve for controlling said gas supply, an actuating winding for opening said gas valve, a room thermostat movable between two contacts, adapted to engage one at a predetermined temperature and the other at a predetermined lower temperature, a double-pole double-throw season switch, means for connecting said damper motor to said source of power, in one position of said season switch, to move said damper motor to the fire-accelerating position when said room thermostat engages one con-

tact and to the fire-retarding position when said room thermostat engages the other contact, a secondary source of power, and means for connecting said gas valve winding to said secondary source of power in the other position of said season switch when said room thermostat engages said one contact.

2. A control system for a furnace wherein both solid and gaseous fuels are burned, said furnace having at least one controlling damper movable between fire-retarding and fire-accelerating positions and a gas supply, including an exterior source of power, electrically energizable means for controlling said damper associated with said exterior source of power, a self-contained source of power, electrically energizable means for controlling said gas supply associated therewith, a thermostatically operated switch, and means for optionally interconnecting said thermostatically operated switch in series with either the exterior source of power or the self-contained source of power.

3. A furnace control system having dual optionally selective control circuits, including a first source of power, a damper motor actuated thereby, a second source of power, an electro-magnetically operated gas valve actuated thereby, a single thermostatic switch and means for interconnecting said thermostatic switch to either said first or second source of power, the construction and arrangement being such that, at will, one of a plurality of control circuits may be established, one from the first source of power through the thermostatic switch to the damper motor and the other from the second source of power through the thermostatic switch to the electro-magnetically operated gas valve.

4. Controlling system for a furnace adapted to burn both solid and gaseous fuel, said furnace having at least one controlling damper movable between fire-retarding and fire-accelerating positions, and a gas supply, the combination of a main source of power, a damper motor for moving said damper from one of said positions to the other, a normally closed gas valve for controlling said gas supply, an actuating winding for opening said gas valve, a room thermostat movable between two contacts, adapted to engage one at a predetermined temperature and the other at a predetermined lower temperature, a double-pole double-throw season switch, means for connecting said damper motor to said source of power in one position of said season switch to move said damper motor to the fire-accelerating position when said room thermostat engages one contact and to the fire-retarding position when said room thermostat engages the other contact, a secondary source of power, means for connecting said gas valve winding to said secondary source of power in the other position of said season switch when said room thermostat engages said one contact, a single-pole double-throw basement switch having a "normal" position through which said motor is connected to said source of power by said thermostat, and

means for shunting the one contact of said thermostat through said season switch in its one position by movement of said basement switch to its other position, whereby movement of said season switch to its other position interrupts said shunt circuit.

5. A condition control system having dual optionally selective control circuits, each including an individual source of power and a device to be energized thereby, an energization control element responsive to changes in the condition to be controlled, means for placing in a selected circuit the condition responsive element thereby controlling the energization of the selected circuit, and manually operable means in one of said control circuits for shunting the condition responsive element permitting manual energization of such circuit.

6. For a furnace wherein two unrelated fuels may be selectively used, a control system including two separate control circuits, one for each type of fuel, an independent source of power for each circuit, regulating means in each circuit for controlling the rate of fuel combustion, a temperature responsive instrument, and means for making the temperature responsive instrument a part of either circuit, the construction and arrangement being such that the temperature responsive instrument will control the regulating means of either circuit when made a part of such circuit.

7. A control system for a furnace wherein both solid and gaseous fuels are burned, said furnace having at least one controlling damper movable between fire-retarding and fire-accelerating positions and a gas supply, including an exterior source of power, electrically energizable means for controlling said damper associated with said exterior source of power, a self-contained source of power, electrically energizable means for controlling said gas supply associated therewith, a thermostatically operated switch, and means for optionally interconnecting said thermostatically operated switch in series with either the exterior source of power and the damper controlling means or with the self-contained source of power, and electrical means for controlling the gas supply.

8. A control system for a furnace wherein both solid and gaseous fuels are burned, said furnace having at least one controlling damper movable between fire-retarding and fire-accelerating positions and a gas supply, including an exterior source of power, electrically energizable means for controlling said damper associated with said exterior source of power, a self-contained source of power produced by heat generated by said gaseous fuel, electrically energizable means for controlling said gas supply associated with said self-contained source of power, a thermostatically operated switch, and means for optionally interconnecting said thermostatically operated switch in series with either the exterior source of power or the self-contained source of power.

CARL H. DICKE.
